UNITED STATES PATENT OFFICE.

EDWARD A. LONG, OF NEW CASTLE, PENNSYLVANIA.

CONCRETE-BLOCK MACHINE.

Application filed March 13, 1926. Serial No. 94,572.

The object of my present invention, broadly speaking, is to provide a concrete-block forming machine, that is to say, a machine for forming the body portions of blocks 5 made of concrete, or the like, the blocks so formed being what is designated as "brick art blocks"; said machine being comparatively simple in character, strong and durable in construction, positive in action; adapted 10 to release and move the blocks formed thereby on straight lines, that is directly downward and outward; said machine being easily operated and controlled by hand, and designed to afford a maximum of efficiency 15 with a minimum of time and expense devoted thereto.

More specifically stated, my object is to provide a machine adapted to receive the face portion of a concrete block previously 20 formed in the manner set forth in Letters Patent No. 1,571,849, which was issued to me on February 2, 1926, and to apply thereto the body portion of the block being constructed.

Other objects and particular advantages of 25 my invention will be suggested in the course of the following description, and that which is new and useful will be correlated in the appended claims.

The preferred manner of carrying out the principles of my invention in a practical and efficient way is shown in the accompanying four sheets of drawings, in which—Figure 1 is a front elevation of my machine. Figure 2 is a rear elevation of the same. Figure 3 is a left-hand side elevation of the same. Figure 4 is right-hand elevation of the same. Figure 5 is a detail view of the draw-table, and its operating mechanism. Figure 6 is a 30 plan view of the carrier member of the draw-table for the table operating mechanism. Figure 7 is a perspective view of the sliding member of the draw table operating mechanism. Figure 8 is a plan view of the handle and shifting means for the draw table operating mechanism. Figure 9 is a front elevation of the mechanism shown in Fig. 8, showing its connection with the draw table. Figure 10 is a plan view of the turn-over 35 table. Figure 11 is a cross section of the turn over table. Figure 12 is a top plan view of the draw table mechanism. Figure 13 is a cross section of the draw table mechanism. Figure 14 is a plan view of the core holder. Figure 15 is a plan view of the hinged side 40 of the mold box. Figure 16 is an end eleva-

tion of the hinged side of the mold box. Figure 17 is a perspective view of the complete machine, showing the mold box as turned over, and showing a finished concrete block on the draw table after the block has been released from the mold box, and showing the draw table as moved outward with the released concrete block thereon. Figure 18 is a perspective view of the face 60 plate for forming the face of the block proper and prior to its insertion into the machine. Figure 19 is an end elevation of face plate and the face portion of a block formed thereon. Figure 20 is a cross section of a 65 completed block. Figure 21 is an inside face view of the upper portion of the right-hand member of the main frame. Figure 22 is an edge view of one of the end-gate holders. Figure 23 is a face view of the same parts 70 shown in Fig. 22, taken at right-angles thereto. Figure 24 is a side elevation of one of the end gates alone. And Figure 25 is a top 75 plan view of one of the end gates alone. Similar indices denote like parts throughout 80 the several views. In order that the construction, the operation, and the several advantages of my invention may be more fully understood and appreciated, I will now take up a detailed description thereof, in which 85 I will set forth the same as fully and as clearly as I may.

Referring now to the drawings in detail: Numeral 1 denotes the left and numeral 2 the right-hand main members of the frame of 90 my machine, which members are substantially identical with each other, and they stand in vertical position parallel with each other.

Intermediate their centers and lower portions the same members 1 and 2 are rigidly 95 connected by cross-bars 5 and 6, the former being in the front and the latter in the rear, as shown in Figs. 1 and 2, respectively. Said cross bars are secured to the end members at each end in any well known manner, as by 100 means of bolts.

Secured horizontally to the inner face of the member 1 is a channel member or track 7; and a like track member 8 is secured to the inner face of the member 2. The members 7 and 8 are located directly opposite to each other, and on the same level, and they are adjustable with relation to the end members 1 and 2. Said members 7 and 8 have channels facing each other, and formed 105 through the central portions of the base of each and extending longitudinally thereof.

are slots, which slots register with the respective slots 9 and 10 which are formed through the respective members 1 and 2.

Cogged racks 11 and 12 are secured on the upper faces of the lower flanges of the respective members 7 and 8. And located inside the channels of the members 7 and 8 are the respective cog-wheels 13 and 14, which mesh in the respective racks 11 and 12, with one side of said wheels contacting with the base of their respective members 7 and 8. A shaft 15 extends through the slots 9 and 10, and on which the wheels 13 and 14 are mounted. Said shaft is prevented from end-wise movements by collars, as the collar 16 shown in Fig. 3, which collars contact with the outer faces of the respective members 1 and 2. Secured on the projecting right-hand end of the shaft 15 is a hand-wheel 18, by which the shaft 15 and the wheels 13 and 14 may be rotated by turning said wheel 18.

Numeral 19 denotes the draw-table, which has flanges 19^a and 19^b extending out from the ends thereof, which flanges are slidably mounted in the channels of the members 7 and 8, and inward from said racks. Said shaft 15 is revolvably mounted in a bearing 15^a which is integral with the rear side of the table 19, whereby the table 19 will be carried forward and backward with the shaft 15 as said shaft is revolved. The forward and backward movements of the shaft 15 being caused by the wheels 13 and 14 operating in their racks 11 and 12, as the wheel 18 is turned by hand.

Formed integral with the under side of the table 19, and at each corner thereof, are the bases 90 through each of which is formed an aperture 91, shown in Fig. 12, which apertures continue up through the top of the table 19 and in which are slidably mounted the pins 20, with their heads adapted to rest on the top of the table when they are down to their limits of movement. Fitting inside of the table 19 is an I-shaped member 21 (Fig. 6) with its four extremities reaching underneath the four apertures 91 in which the pins 20 operate, whereby the lower ends of said pins 20 rest on the said corners of the member 21, to which they are secured, whereby the raising or lowering of the member 21 will lower or raise all of the pins 20 together, that is at one time.

Secured on the underside and in the center of the member 21 is the smaller triangular block 22, and in sliding contact therewith is the larger sliding triangular block 23; the diagonal faces of the blocks 22 and 23 are in contact with each other, and they operate at right-angles to the length of the member 21, that is to say,—the block 23 is adapted to move forward and backward in contact with the block 22. The block 23 is mounted on the bar 24, whose ends are slidably mounted in apertures formed through the

front and the rear sides of the draw table 19. The forward end of the bar 24 is pivoted to the small shaft 25, as at A in Fig. 8. The other end of the shaft 25 is pivoted at B to the block 26, the latter being pivoted at C to a projection from the front of the lower portion of the table 19. The handle 27 is secured to the block 26 whereby said block may be turned laterally as desired.

It will now be seen that if the handle 27 be turned to the right and the left that it will cause the member 21 to be raised and lowered, thereby raising and lowering the pins 20. In practice if the handle 27 be turned to the left the pins 20 will be lowered, and if turned to the right the pins will be raised. Also it should be noticed that by reason of the construction shown that the pins 20 will be locked in either their raised or lowered position, for the reason that the block 26, and the connections therewith, acts as an eccentric.

Extending back from the members 1 and 2 are the respective extensions 28 and 29, which have horizontal upper edges, as shown.

Extending between the members 28 and 29 is the core operator shaft 30, on which is mounted the core operators 31, hereinafter referred to in this description.

Extending rearward and upward from the rear corners of the extensions 28 and 29 are the respective arms 32 and 33 which carry the core shaft support 34.

Secured on the projecting left-hand end of the shaft 30 is the operating lever 35, by which said shaft may be rotated.

Numerals 36 and 37 denote brackets which are adjustably secured on the upper edges of the respective extensions 28 and 29, by the respective pairs of bolts 38 and 39. The upper portions of the brackets, 36 and 37, are connected by the core holder 40.

Numeral 41 denotes the turn-over table, which is revolvably connected to the end members 1 and 2 by trunnions 42 and 43, which are mounted in bearings carried by said members 1 and 2, as the bearing 44, shown in Figs. 3 and 4. Extending longitudinally through the table 41 is a shaft 45, the same being concentric with and extends through said trunnions. On the projecting left-hand end of the shaft 45 is secured the hand-wheel 46, by which said shaft may be rotated. Inside the table 41 the shaft 45 is threaded, one-half of the threads being right-hand and the other half left hand, as in Fig. 10, for the purpose hereinafter explained.

Extending up from the surface of the table 41, and slideable thereon, are the two end gate members, 47 and 48, which form the ends of the mold-box which is located on the table 41. Secured across the inner face of each of the end gate members 47 and

48, is an end mold 95 and 96 respectively, which forms the indentations in the ends of the block P. Said end gate members, 47 and 48, are detachably secured in upright 5 position each by an end gate holder or standard, 70 and 71 respectively, the lower positions of which are adapted to move in the channel Y, Fig. 11, which is located longitudinally in the center of the table 41, with their lower end portions threaded on the shaft 45, one being operative on the right and the other on the left-hand threads of the shaft 45. Secured on the outer faces of the end gates 47 and 48 are the respective U-shaped catches, 83 on the right and 84 on the left gate, through which the upper portions of the respective members 70 and 71 pass. There being hook-springs 85 and 86 carried by the members 70 and 71, respectively, which engage the respective members 83 and 84 to hold the end gates 47 and 48 in operative position. When desired it is evident that by simply pressing inward on the upper ends of the springs 85 and 86 15 the members 47 and 48 may be easily and quickly released and lifted upward and removed.

When the members 47 and 48 are in operative position, it is apparent that when 30 the wheel 46 is rotated that they will move toward and from each other, depending on which way the wheel is rotated, for the reason that they will be carried by the end gate holders 70 and 71 which in turn are connected with the shaft 45.

Numeral 49 denotes the fixed side of the mold box, which is secured to the top of the table 41 by a plurality of brackets 50, and it normally remains in this fixed position, 40 except that it can be adjusted for various sizes of work. The other side 51 of the mold box is similar to the side 49, but it is hinged to the table 41, by hinges 3 and 4, whereby it can be turned up parallel with the side 49 to complete the sides and ends of the mold box, or it can be turned at right angles, to open the mold box as in Fig. 17.

Formed through the member 51 are the 50 three large core apertures, D, E and F, Fig. 15, and the two small core apertures G and H.

Secured to the inner face of the member 51 are the two molding blocks 17, shown in Figs. 16 and 17, and their locations are indicated in dotted lines in Fig. 15. Said blocks 17 extend from the apertures G and H to the top edge of the member 51, that is to the upper line shown in Fig. 15, for the purpose hereinafter stated.

Numerals 5 and 6 denote stop brackets 60 which are adapted to support the hinged side 51 of the mold box in operative position while the mold is being filled. Said brackets extend forward from the core holder 40 to which they are secured.

Formed through the core holder 40 are

three core apertures I, J and K, which correspond in size and register with the apertures D, E and F; and the apertures L and M correspond in size and register with the apertures G and H.

The large cores 60, 61 and 62 are supported by and slide in the respective apertures I, J and K, and through the apertures D, E and F, with their forward ends adapted to extend entirely across the interior of the 75 mold box, to the forward side 49 thereof.

Said cores 60, 61 and 62 are retained in proper spaced relation to each other by the core support 40, which in turn is held by the shaft end support or holder 72, and extending rearward from the latter are the core shafts or guides 63, 64 and 65.

Numerals 73 and 74 denote the small cores, which have their rear ends connected with the holders 70 and 71, and they operate simultaneously with the cores 60, 61 and 62, and they slide through their respective apertures L—M and G—H, but they extend only about half-way through the mold box.

Numeral 69 denotes a lug carried by the mold box which when the mold box is turned from its inverted position shown in Fig. 17, to upright position as in Fig. 1, that it can only go to a point sufficient to bring the table 41 to exact upright or horizontal position as in Fig. 4, at which latter position the lug 69 will engage with a projecting portion of the member 2 of the main frame.

Secured to the right-hand end of the turn-over table 41 is the handle 59, by which said table may be turned 180°, turning on the trunnions 42 and 43. By means of the small plunger 75, shown in Fig. 10, which is operated by the auxiliary, spring actuated, lever 76, the turn over table may be locked and unlocked in either upright, or half turned over position, or at an angle, as the plunger 75 may be entered in either of the sockets 105 110 hereinafter described.

In Fig. 21 is shown three lugs, 92, 93 and 94, which extend inward from the inner face of the upper portion of the member 2, and in each of said lugs a socket is formed, 115 as the respective sockets 87, 88 and 89, which are adapted to receive the free end of the plunger 75. When the plunger 75 is in socket 87 the turn over table will be in inverted position, as in Fig. 17, while if it be 120 in the socket 89 the table will be in upright position, as in Figs. 1, 3 and 4; and when the plunger is in socket 88 the said table will be held at an angle, which is the position required to insert the facing plate 79, carrying 125 the face portion of a new block. Formed through the top of the table 41 are four apertures 77, which are adapted to receive the respective four beveled lugs 78 which are formed integral with the underside of 130

the facing plate 79, where they are adapted to be rigidly secured by clamps or other means as desired.

The face N of the block to be formed by this machine is indicated in Fig. 19, and the backing therefor is indicated by letter O. The said parts, N and O, having previously been made on the plate 79, as set forth in said Patent No. 1,571,849. The body of the concrete block to be made by the machine now being described is indicated by the letter P, as shown in Fig. 20.

Numeral 52 denotes the pallet board or top of the mold box, and it is adapted to rest on the edges of the sides and the ends thereof whereby it may be secured by the clamps 53 and 54 which fit over the ends of the member 52, as shown in Figs. 3 and 4. Said clamps are adapted to be tightened or loosened by eccentrics which are operable by the levers 55 and 56 in front, or by the levers 57 and 58 in the rear, the operation of either set of levers accomplishing the same results.

Secured to the shaft 30 are the core operating arms 31, the upper ends of which are slidably connected with the rear end of the holders 70 and 71. The core operating arms 31 are operable by the operation of the lever 35, through the operation of the shaft 30, whereby the cores 60, 61, 62, 73 and 74 may be driven forward and backward in direct horizontal lines, all operating synchronously. When the concrete block is completed, as shown in Fig. 17, the apertures Q, R and S will have been formed therethrough by the cores 60, 61 and 62, respectively. The cavities T and U having at the same time been formed by the cores 73 and 74; and the notches V and W are formed by the blocks 17; and at the same time the impressions in the ends of the block will be formed by the molds 95 and 96. When opened out, as in Fig. 17, the side 51 may be retained in open position by means of the latch 80, as shown in Fig. 17.

The eccentrics 55 and 56 are adapted to be adjusted laterally in their slots 81 and 82, whereby the end gate members of the mold box can be located to form various lengths of blocks P, and also to free the block when it is ready to be removed.

Operation.

The face of a concrete block to be formed by this machine is first prepared on a facing plate 79, as set forth in Patent No. 1,571,849. Said plate containing the face portion N and its backing O is then placed on the table 41, with the lugs 78 fitting in the openings 77 of the table 41, where they are securely clamped, this being done while the table is turned at an angle as stated.

The above will bring one edge of the plate 79 against the side 49.

65 The end gates 47 and 48 are then brought

toward each other by turning the wheel 46 until the end gates are the proper distance apart to form the block of the desired length, that is until the end gates are brought into contact with the ends of the plate 79.

The hinged side 51 of the bold box is then turned on its hinges, 3 and 4, bringing it to vertical position, that is parallel with the fixed side of the core box. The lever 35 is then turned forward, turning the shaft 30, and causing the core operating arms 31 to force the core members 60, 61, 62, 73 and 74 through the apertures D, E, F, G and H in the side 51, and extending them into the mold box, the first three extending entirely across the mold box and the two latter only about half-way across the interior of the mold box.

The mold box may now be filled with concrete mixture, filling around the cores and various other parts inside the mold box, and extending it up even with the top of the mold box and tamping it down compactly, after which the pallet board, forming the lid, is placed in position thereon, as in Fig. 1. The clamps 53 and 54 are then turned inward over the ends of the pallet 52, and the eccentrics 55, 56, 57 and 58 are then turned by means of their respective handles whereby the clamps will rigidly secure the pallet 52 in position.

The next operation is to turn the lever 35 rearward, which will draw the cores 60, 61, 62, 73 and 74 from the interior of the mold box, thereby leaving their impressions in the body P. I then grasp the handle 59, at the same time grasping the lever 76, and withdrawing the plunger 75 from its socket, then by pressing forward on the lever 59 the entire mold box, and the other parts attached thereto, including the concrete block in process of construction, may be given a half turn which will bring the parts to inverted position.

Now by turning the wheel 18 it is evident that the draw table 19 may be brought directly under the pallet 52, which has now become the bottom. I then turn the handle 27 to the right, it having previously been to the left, which will force the pins 20 upward into contact with the pallet 52, which will support the block when it is released. I then release the clamps 53 and 54 and swing them outward and apart to where they are shown in Fig. 17, which will release the pallet 52 and allow it, together with the block being formed, all to be supported by the pins 20. I then release the side 51, turning it on its hinges 3 and 4, and swing it to the position in which it is shown in Fig. 17, where it may be secured by the latch 80. I next revolve the wheel 46 to withdraw the end gates 47 and 48 from the block, moving them in a straight line and in directions opposite to each other. The block will now be

freed from the mold box, except its contact with the vertical face of the fixed side 49. Therefore I next slowly turn the handle 27 to the left, which will lower the pins 20, whereby the pallet 52 will be lowered, also the concrete block carried by the pallet, moving the same downward in a straight line until the block is entirely free and ready to be moved forward or outward. I then turn 10 the wheel 18 whereby the draw table 19, which now carries the new block, will be carried forward from under the mold box, and bringing it to such position that the pallet 52 may be manually lifted, with the 15 finished block thereon, and carried away and stacked for the proper time for curing the block and for drying.

It should be noticed that the openings V and W, in the block, will have been formed 20 by the mold blocks 17, which are secured to the inner face of the side 51 of the mold box, and then when said side is turned outward, as shown in Fig. 17, the said blocks 17 will be withdrawn, thereby leaving their impressions V and W in the completed concrete 25 block.

After the concrete block has been completed, removed from the machine, and disposed of, then the handle 59 may be grasped 30 and the mold box be turned back to about 30' position, after which the draw table may be moved back to position under the mold box by turning the wheel 18, after which the operations above set forth may be repeated 35 as before stated. First removing the facing plate used in the block just completed, and a new facing plate 79 containing the face portion for a new block is inserted in the machine as previously set forth.

40 The impressions V and W formed by the blocks 17, and the cavities T and U, formed by the cores 73 and 74, may be filled each with a wooden block, to providing nailing means if desired. The same being set forth 45 in my pending application for patent, Ser. No. 27,295, filed May 1, 1925.

I desire that it be understood that various changes may be made in the several details herein set forth without departing from the 50 spirit of the invention and without sacrificing any of the advantages thereof which are new and useful and which involve invention.

Having now fully shown and described my invention, and the best means for its 55 construction and operation to me known at this time, what I claim, and desire to secure by Letters Patent of the United States, is—

1. A concrete block forming machine comprising a main frame composed of spaced 60 end members, a turn-over mold box rotatably mounted between the end members and comprising a table, a fixed side secured on the table, a second side hinged to the table and adapted to extend parallel with the 65 fixed side or to be turned outward therefrom

on hinges, end members adapted to connect the ends of the two sides, means for moving the end members synchronously toward and from each other, a pallet forming a cover for the mold box and adapted to rest on the 70 sides and the ends, clamps for holding the pallet in said position, and means for turning the mold box upside down, all substantially as set forth.

2. A concrete block forming machine comprising a main frame composed of spaced end members, a block forming enclosure including a table with its top forming the bottom of the enclosure, a fixed side extending up from the table, a hinged side connected 75 with the table, ends slidable on the table toward and from each other, a cover to rest on the upper edges of the sides and the ends, clamps for holding the cover in place, trunnions extending from the ends of the table 80 and mounted in bearings carried by the end members, cores adapted to slide horizontally through apertures therefor in the hinged side, means for moving said cores inward and outward, and means for turning said 85 enclosure upside down on said trunnions.

3. A concrete block forming machine comprising a frame comprising two end members spaced apart and rigidly connected together, a block forming enclosure including 90 a table, a fixed side extending up from the table, a hinged side connected with the table, end members slidably mounted on the table, a top for the enclosure, means for securing the top in closed position, trunnions projecting from the ends of the table and supported by bearings carried by the end members of the frame, a plurality of cores mounted to slide into the mold box through apertures formed through the hinged side, 95 a lever for projecting said cores into the core box and for withdrawing them therefrom, means for turning said enclosure upside down, and a draw table located underneath the enclosure when the enclosure is 100 upside down, means carried by the draw table for receiving the top of the enclosure and lowering it together with a completed concrete block thereon, and means for carrying the draw table horizontally from underneath the enclosure.

4. A concrete block forming machine comprising the main end members of the frame, a mold-box table, trunnions formed at the ends of the table and adapted to operate in 110 bearings carried by the main frame, a shaft extending through the members of the main frame and through the table and through said trunnions, a fixed side carried by the said table, a hinged side carried by the said table, two end gate members carried by the table and adapted to be moved toward and from each other by the rotation of said 115 shaft, a cover adapted to rest on the upper edges of said sides and ends, means for 120

125

130

clamping the cover in place, cores adapted to move horizontally through apertures in said hinged side and projecting into the space between said sides and ends, means for operating said cores horizontally, and means for giving said table a half-turn after a concrete block has been formed in the enclosure formed by said sides and ends and after the cores have been withdrawn therefrom.

5. A concrete block forming machine comprising a main frame, a mold box table, trunnions permitting said table to be revolved in the frame, means for locking the 15 table in upright or inverted position, a mold box enclosure mounted on said table and comprising a fixed side, a hinged side, end members, and a top; cores adapted to be driven horizontally into the mold box 20 through apertures in the hinged side, said cores comprising a plurality of major cores and a plurality of minor cores, means carried by the inner face of the hinged side for molding spaces in the block to be formed 25 in the mold box, which notches will connect with and be at right-angles to the spaces formed by the minor cores, means for securing a matrix plate on said table and inside the mold box which matrix has the face 30 portion of a concrete block carried thereon, the interior of the mold box to be filled with concrete compost with said top resting on the compost in the mold box, means for withdrawing all of the cores simultaneously 35 from the mold box, means for giving the table and the mold box and the block formed in the mold box a half turn, and means for lowering the completed block in a straight line and then carrying it out from underneath the mold box.

6. A concrete block forming machine comprising a main frame composed of end mem-

bers spaced apart, a turn-over mold box rotatably mounted between the end members and comprising a table, a fixed side for the 45 table, a hinged side for the table, end gates coacting with said sides and adapted to be moved toward and from each other, a pallet forming a cover for said mold box, trunnions by which said table is rotatably 50 mounted, cores adapted to be projected into the mold box and removed therefrom, means for turning the mold box after a block has been formed therein and whereby said pallet becomes the bottom of the mold box, a draw 55 table adapted to receive the pallet with the block thereon and lower them in a vertical line, and means for causing the draw table to move outward in a horizontal line to free the block from the machine.

7. A mold for forming concrete blocks, said mold comprising a turn-over table, a side extending up from one edge of said table and rigidly secured thereto, a second side member hinged to the other edge of said table, end gate members adapted to move toward and from each other and adapted to connect said sides, means for moving said end gate member in opposite direction at the same time, a pallet completing the enclosure of the mold, a plurality of cores adapted to project into the interior of the mold to remain therein during the time the block is being formed in the mold, means for removing said cores after the block has been formed in the mold, means for giving the mold a half turn-over with the block therein, means for releasing the block from the mold, a draw table adapted to receive the block from the mold and by which the 75 block may be lowered directly downward 80 and then moved directly outward.

EDWARD A. LONG.
